2,177,734

METHOD OF REFINING PETROLEUM OIL IN PROPANE SOLUTION

Claude P. McNeil, Whiting, Ind., assignor to Standard Oil Company, Chicago, Ill., a corporation of Indiana

Application December 23, 1936, Serial No. 117,288

9 Claims. (Cl. 196—34)

This invention relates to refining processes employing propane, and more particularly to the refining of hydrocarbon oils wherein the oils are acid treated and neutralized in propane solution.

5 The object of the invention is to provide a system which will prevent loss of propane in the recovery system, thus not only avoiding a waste of valuable products, but preventing the escape of propane vapors. A further object is to minimize 10 the amount of caustic required in the process by employing partially spent caustic in place of fresh caustic. A further object is to avoid pumping costs and to provide a more compact and more efficient but less expensive process than has 15 heretofore been available. The invention also contemplates further improvements in the process of propane deasphalting, acid treating and neutralizing of heavy residual lubricating oil stocks, all of which will be more clearly apparent 20 from the following detailed description:

In processes wherein residual oils are fractionated by means of propane, and wherein the propane-oil solutions are thereafter acid treated and neutralized, it has been the practice to discharge 25 the spent caustic from the neutralization step to the sewer on the assumption that propane was relatively insoluble therein. I have discovered that this spent caustic wash which is withdrawn from the caustic settler apparently contains relatively large amounts of propane, probably in 30 emulsified form or dissolved in emulsified oily products. The discharge of this caustic wash to the sewer therefore gives rise to the loss of valuable propane and at the same time it presents a 35 dangerous fire hazard.

Also, in prior practice it has been found that the propane liberated in the acid sludge hydrolysis step contains acidic substances which must be eliminated from the gases before they are returned to the compressor. Heretofore it has been the practice to not only scrub these gases with water but to add caustic to the scrubbing liquid for the neutralization of these acidic substances. I have discovered that by the extremely simple 45 expedient of passing the spent caustic solution from the caustic settler to the top of the scrubber in which the acidic gases from the sludge hydrolysis are to be neutralized, I can recover valuable propane from the spent caustic wash liquid. Also, 50 this spent caustic is sufficiently active to neutralize the acidic vapors and gases from the hydrolysis of the acid sludge. Thus I avoid the necessity of adding fresh caustic for the neutralization of acidic gases and at the same time prevent any 55 loss of propane. Furthermore, I have found that

the spent caustic may be transferred from the caustic settler to this gas scrubbing system by the pressure differential in the system and without the necessity of employing special pumps.

The invention will be more clearly understood by reference to the accompanying drawing which forms a part of the specification and in which: Fig. 1 diagrammatically represents an elevational view of my improved propane-oil refining system, and Fig. 2 is a cross section detail taken along the lines 2—2 of Fig. 1.

The invention will be described as applied to the treatment of a residual Mid-Continent petroleum stock reduced by noncracking distillation to a viscosity of about 400 seconds Saybolt at 210° F. 15 It should be understood, however, that the invention is equally applicable to the treatment of any and all residual or distillate stocks as well as the treatment of synthetic oils and oil products, particularly products produced by the polymerization 20 of hydrocarbons, the condensation of hydrocarbon radicals with aromatics, products produced by oxidizing, sulfonating, chlorinating or otherwise chemically treating hydrocarbon oils or products, etc.

While the invention is described as employing propane, it should be understood that other normally gaseous hydrocarbons may be employed in place thereof, and the term "propane" is intended to include such hydrocarbons or admixtures 30 thereof with pure propane. In the preferred example I will state conditions for a gas containing only small amounts of butane and ethane,—those skilled in the art will appreciate the necessity for slightly modifying the conditions when gases 35 other than propane are used.

About 3 to 5 volumes of propane from storage tank 10 are introduced through pump 11 and heater 12 to mixer 13 wherein it is intimately mixed with one volume of the Mid-Continent residuum from storage tank 14, steam discharge heater 15, pump 16 and line 17. The propane is preferably added to the residuum in stages 18 to 40 avoid agglomeration of asphalt and the entrainment of propane soluble oil therein.

The propane-residuum mixture is transferred through line 19 to asphalt settler 20, preferably at a temperature of 80° F. to 120° F., or preferably about 110 to 115° F. and at a pressure of about 250 to 400 pounds gauge, preferably about 50 390 pounds. Under these conditions the propane soluble materials separate in an upper layer which is continuously withdrawn through line 21 and pressure reduction valve 22 to mixer 23 55 wherein the solution is intimately mixed with sul-

furic acid from line 24, preferably with about .1 to .4 pound of 93% acid per gallon of residuum charged. The acid oil mixture is introduced into sludge settler 25 through a funnel-shaped device 26 for maintaining quiescence in the settling zone, the pressure in the sludge settler preferably being about 210 to 220 pounds gauge and the temperature being about 105° F.

The sour oil which separates from the sludge is 10 continuously withdrawn from the settler through line 27 into mixer 28 wherein it is intimately mixed with caustic from line 29. The caustic is preferably about a 2% solution and about 0.2 gallon of caustic are introduced per gallon of sour oil (apart from propane) to be neutralized. This 15 is a considerable excess over the amount theoretically required; an excess is necessary to insure that satisfactory neutralization is obtained at all times. The mixture of sour oil and caustic is 20 allowed to settle in caustic settler 30, the neutralized oil being withdrawn through line 31 through heater 32 to oil flash tower 33 which is provided with bubble plates 34 to prevent loss of entrained oil with propane, and which is provided with a 25 reboiler 35 for maintaining a temperature at the base of the flash tower of about 300° F. at a pressure of about 195 pounds gauge.

Oil from the base of the flash tower is withdrawn through line 36 and reducing valve 37 into oil stripper 38, the oil passing downwardly over baffle plates countercurrent to steam introduced through line 39. The oil leaving the stripper at a temperature of about 285 to 290° F. and about atmospheric pressure is withdrawn through line 40 to dehydrator 41 which is simply a baffle tower wherein the hot oil is passed over baffle plates countercurrent to air introduced through line 42. The finished oil is then withdrawn through line 43 to storage 44.

40 Returning to the asphalt settler, the asphalt layer is withdrawn through line 45 in amounts regulated by a liquid level controlled valve and is then passed through preheater 46 into asphalt flash tower 47. Since the asphalt flowing through 45 the preheater tends to flow through the tubes as a solid core, I have found that ordinary exchangers are relatively ineffective but that efficient heat exchange can be obtained by employing concentric tubes and flowing the asphalt solution through 50 the annular space between the tubes, the heat exchange fluid being applied either through the inner tube, around the outer tube or both. By this expedient I minimize the thickness of the layer of asphaltic material to which heat must 55 be applied. I have found that this expedient greatly increases the effectiveness of my heat transfer system. I may also flux the asphalt before heating by admixing charging stock or gas oil or both thru a branch of line 48.

60 The flash tower is preferably maintained at a temperature of about 315 to 320° F. and a pressure of about 195 pounds gauge.

The asphalt from the base of the flash tower is withdrawn through line 49 and reducing valve 65 58 to asphalt stripper 51, wherein it is passed over baffle plate 52 countercurrent to steam introduced through line 53, the asphalt being withdrawn at a temperature of about 240° F. through line 54 to asphalt storage 55.

70 To avoid foaming in the asphalt stripper I may introduce a spray of residuum from line 48 or a spray of gas oil introduced through the same line.

Propane from the asphalt flash tower is withdrawn through line 56 to high pressure propane 75 line 57. Propane from asphalt stripper 51 is in-

troduced through line 58 to line 59, thence to the base of condenser 60 wherein it flows upwardly in the baffle tower countercurrent to water introduced at line 61, the condenser water being withdrawn through line 62 to the sewer. Propane 5 from the top of steam condenser 60 is transferred through line 63 and compressor 64 to the high pressure propane line 57, thence through condenser 65 to propane storage 10.

The acid sludge from the base of settler 25 is 10 withdrawn through line 66, fluxed with gas oil 67 and introduced with steam from line 68 into sludge stripper or hydrolyzer 69. The fluxed sludge flows downwardly over baffle plate 70 countercurrent to steam introduced through line 71 15 and the sludge leaving the system through line 72 is conveyed to the acid works for the separation, recovery and concentration of sulfuric acid.

Propane and acidic gases from sludge stripper 69 are conveyed through line 73 to the base of 20 neutralizing jet condenser 74 which may be described as a scrubbing tower provided with baffles 75 into which water is introduced through line 76 and caustic is introduced through lines 77 and 78. I prefer to introduce the major portion of the 25 caustic with the water since I have found that when too much of the caustic is introduced in line 78 it may cause a clogging of the system.

The caustic which is introduced at the top of the neutralizing jet condenser is supplied through 30 line 80 from the base of caustic settler 30, and since the caustic settler operates at about 200 pounds gauge and the neutralizing jet condenser operates at about atmospheric pressure to 25 pounds gauge, it is necessary that a pressure reduction valve be employed, as indicated, although this valve may, as in the case of the discharge settler, be operated by a liquid-level controlled device. Thus it will be apparent that entrained, dissolved or emulsified propane which is withdrawn from the caustic settler is not passed directly to the sewer as in prior practice, but is passed through lines 77 and 78 to neutralizing jet condenser 74 so that the propane may be recovered from the caustic wash and at the same 45 time the remaining alkalinity of the caustic is utilized for neutralizing acidic gases from the sludge stripper. The water and spent caustic leave the neutralizing jet condenser to the sewer through line 81, relatively free of propane. 50

Propane is removed from the top of the neutralizing jet condenser through line 79 to line 68 and compressor 64.

Propane from oil stripper 38 is withdrawn through line 82 to line 59 and propane from oil 55 flash tower 33 is withdrawn through line 83 to line 57. Moisture-laden air from dehydrator 41 may be vented through line 84.

While I have described in detail a preferred embodiment of my invention, it should be understood that I do not limit myself to any of the details hereinabove described except as defined by the following claims, which should be construed as broadly as the prior art will permit. 60

I claim:

1. The method of refining petroleum oil in propane solution which comprises treating said solution with sulfuric acid and separating sludge therefrom, neutralizing the acid-treated oil with aqueous caustic and separating caustic wash therefrom, recovering propane admixed with acidic gases from the acid sludge and scrubbing said propane and acidic gases with the caustic wash in a closed system whereby any propane entrained in the caustic wash may be combined with 70 75

the propane recovered from the sludge and whereby the unspent alkalinity of the caustic in the wash may be utilized to neutralize the acidic gases admixed with the propane.

5. 2. In a propane deasphalting system which includes the steps of acid treating deasphalted oil, neutralizing said acid-treated oil with aqueous caustic, stripping sludge from the acid treating step, and recovering propane from said sludge and acid-treated oil, the method of conserving both

10 caustic and propane which comprises scrubbing gases from the sludge stripping step with caustic material withdrawn from the neutralization step, and simultaneously recovering propane from 15 the stripped sludge and from the caustic.

3. In a propane treating system, wherein a petroleum oil is first treated with acid and then neutralized with aqueous caustic in propane solution, and wherein an acid sludge layer and caustic wash layer respectively are withdrawn from 20 said steps, the process of neutralizing and recovering propane from said steps which comprises countercurrently contacting the propane removed from the acid sludge with caustic wash, whereby 25 propane is recovered from the wash and acidic materials from the sludge are neutralized, and condensing and compressing the propane from the countercurrent scrubbing system for reuse in the process.

30 4. A hydrocarbon oil refining process which comprises deasphalting a reduced crude at about 110 to 115° F. and under a pressure of about 400 pounds gauge, treating the deasphalted oil in propane solution with about .2 to .3 pound of 93% acid per gallon of stock charged, separating sour oil from acid sludge, separating propane and acidic gases from said sludge, neutralizing the sour oil with aqueous caustic, separating the neutralized oil from the caustic wash, neutralizing 35 the propane recovered from the acid sludge with the caustic wash and simultaneously recovering the propane from said sludge and said caustic wash recycling said recovered propane for the treatment of more oil.

5. The combination of claim 4 wherein the separated asphalt is heated in an annular zone and propane is recovered from the heated asphalt.

6. The method of claim 4 wherein neutralized oil is freed from propane and dehydrated by blowing with air at a temperature of about 250 to 300° F.

7. The method of claim 4 wherein propane is removed from acid sludge by direct steam stripping.

8. In a process of refining lubricating oils by acid treatment in propane solution followed by neutralization of the sour oil with caustic wherein acid sludge is separated in the acid treated step and caustic wash is separated in the neutralization step, the method of recovering propane from propane acid sludge and caustic wash liquid respectively which comprises contacting said acid sludge with steam for removing propane therefrom and scrubbing said separated propane with 20 said caustic wash and water for condensing said steam, neutralizing acidic gases and combining the propane of the caustic wash with the propane separated from the sludge.

9. In a propane treating system wherein a petroleum lubricating oil stock is treated with acid in propane solution, the acid sludge is separated from the treated oil, the treated oil is neutralized with a caustic solution and a caustic wash liquid is separated from the neutralized oil, the method 30 of utilizing the caustic wash liquid and avoiding loss of propane which comprises hydrolyzing the sludge with open steam whereby the heat of hydrolysis supplements the heat of the steam for distilling propane from the sludge, contacting said propane with said caustic wash liquid for removing any acidic gases that may be associated with the propane to condense the steam, and to recover the propane dissolved in said caustic wash liquid, and returning the neutralized and recovered propane for the treatment of more oil.

CLAUDE P. MCNEIL.
